UDO K. JOHANNSEN, OF CORTLAND, NEW YORK, ASSIGNOR TO THE BREWER-TITCHENER CORPORATION, OF CORTLAND, NEW YORK, A CORPORATION OF NEW YORK

METHOD OF MAKING TRIM FRAMES

Original application filed January 8, 1932, Serial No. 585,585. Divided and this application filed July 14, 1932. Serial No. 622,428.

This invention relates to the art of a built-up, sectional moulding or the like, and is more particularly directed to improvements in a decorative, rectangular frame-work intended for panel trim purposes and which endless sheet metal moulding comprises but four rectilinear segments that can be economically fabricated from strip stock and rapidly secured together at their intersecting regions without surface defacement by welds, rivets or need of separately formed corner pieces or the like superfluous keeper means.

The primary object of my invention is to provide for a smartly designed trim frame of the character indicated and one that can also be cooperatively applied to the perimeter of a beaded panel. My fenestrated frame design is such that it can be made up to any desired dimension by the use of relatively few forming dies and still provide for rounded corner regions. The present segmental structure is preferably struck up out of relatively narrow sheet metal into complementary pairs of dished side and cross bar sections of similar transverse profile having their respective ends overlappingly nested and neatly united by flexible tonguelike or equivalent fastening means, the terminals of said bars being preferably offset and so disposed that their respective front faces fall into substantial alignment. Said moulding may be supported upon its embraced panel and secured thereto by the use of a plurality of spaced prongs depending from the rounded perimeter of the frame assembly and which prongs may be overlappingly inturned against the rear of the mounted panel.

The present application is a division of my Serial No. 585,585 as filed January 8, 1932 and the improvements herein treated consist in a novel method for making my moulding frame, all of which will hereinafter be disclosed in detail. Reference is had to the accompanying one sheet of drawing, which is illustrative of a specific embodiment of my invention, and in which drawing:

Fig. 1 shows an elevational front view of my preferred style of frame assembly provided with rounded corner regions as applied

to a conventional license plate or panel, while Fig. 2 represents a rear view thereof with the frame prongs crimped inwardly to mount the panel therebehind.

Fig. 3 is a fragmental sectional view of 55 said assembly as taken along line 3—3 of Fig. 1.

Fig. 4 illustrates an enlarged corner detail of Fig. 2 and the relation of the frame prongs prior to their being crimped inwardly.

Figs. 5 and 6 respectively represent a side-bar and a cross-bar blank as stamped up from flat strip stock.

Figs. 7 and 8 are typical perspective views 65 of the respective blank ends after they have been formed up and made ready for assembly into the rectangular Fig. 1 framework.

A detailed description will first be directed to the structural aspects of my frame; 70 Figs. 1 to 8 collectively show a built-up framework or endless moulding of channel-like profile adapted to trim the marginal edge of an elongated automobile license plate 10 or any other similar panel. The 75 prevailing State identification plates are commonly provided with an endless marginal bead 11 and with an adjacent inner groove such as 12. The corner region of the plate perimeter is generally rounded off as 80 represented at 13 by dotted outline in Fig. 4. The panel 10 is placed behind the fenestration of my open rectangular skeleton frame of which the upstanding pairs of relatively long corner prongs 14 and 15 are crimped 85 over the panel edge in the fashion indicated in Fig. 2. My segmental framework is characterized by the use of sheet metal side-bars and cross-bars such as 16 and 17 respectively and which bars are kept rectilinear except 90 at the overlapping terminal regions thereof. Short supplemental bar tongues such as 18 and 19 respectively, may be used to permanently clinch together the overlapping nested frame-bar ends, which built-up method 95 materially reduces production costs over an integrally stamped frame which latter involves considerable waste in center plate stock.

The improved mode of making my frame 100

may be explained in connection with Figs. 5 and 6. The first named figure shows a striplike blank 20 provided with quadrant or the like rounded ends as at 24A and which 5 blank is stamped out of flat cold rolled strip stock of suitable sheet metal gauge and width "w". Said blank is preferably given a dished or channel-like profile comprising a relatively flat web element 16A disposed 10 between upstanding marginal flanges such as 16B and the respective ends of which web may be raised to constitute a socketed, rectilinear side-bar 16 (see Fig. 7). The opposite blank ends may be similarly but reverse- 15 ly sheared while still flat to include a relatively short end tongue 18, a side tongue 19, and an intermediate relatively long extension or prong 14 that is parted by an edge indentation or inset gap 21, all of which ele- 20 ments are kept within the confines of the strip width "w". The dotted outline indicates the corresponding die contour and the manner of parting said endless strip in a plurality of such blanks of any desired over- 25 all length, depending upon the successive feed-spacing that is given to the strip stock.

Fig. 6 represents the corresponding flat shape that may be imparted to my relatively shorter blank 22 as kept free of any tenons, 30 but made to terminate in the oppositely disposed prongs 15 and also provided with spaced tongue receiving apertures such as 23. Between such apertures and their respective overhanging prongs, the blank perimeter 35 may be given a nose-like quadrant contour such as 24, which shape in turn allows of subsequently giving the respective corner regions of my otherwise rectangular framework, an upturned, rounded perimetric for- 40 mation of which the radius R is kept substantially equal to the strip width "w". If desired, one strip edge contiguous to the prong end region may be indented or inset at 21A as shown. The blank 22 is then 45 struck up by the use of suitable dies into a dished cross-bar 17 of channel shaped profile having a relatively flat web element 17A and reversely disposed terminals with the prongs 15 thrown downwardly as shown in Fig. 8 where the end region of the innermost 50 web flange 17B is cut away at 21A and is kept relatively shorter than the outermost mated flange. Each terminal of the side-bar 16 may be transversely offset at 29 to form a 55 bar extension 26 and constitute an interiorly socketed means adapted to overlie and snugly nest the described cross-bar terminal, thereby maintaining the plane of the respective bar webs 16A and 17A in substantial 60 alignment with a common face of the panel 10, the upstanding web flanges all being faced in one and the same direction.

A distinctive structural feature of my built-up framework resides in the novel for- 65 mation given to the respective corners there-

of; the rectilinear bar sections may each be perimetrical rounded to constitute an overlapping corner region of sector shape such as is depicted in Fig. 4. These intersecting bars are interconnected by the tongue 19 along one radially disposed edge of said shape while the complementary tongue 18 clinches together the superimposed bars along the rounded perimetric edge thereof. The clinchable, panel retaining prongs 14 70 and 15 are shown spacedly associated with opposite end regions of the rounded contour of said sector shape to lie within the projected width confines of the respective sheet metal strips of which they form an integral 75 part.

In the Fig. 7 disclosure, the exposed exterior face of the socket 26 is kept raised outwardly beyond the offset 29 to provide for a neat corner trim that protrudes upwardly relative to the intermediate face portion of the frame-bar 16 and which offset aligns with one radial edge of the overlapping, sector-shaped bar region. The opposed radial edge is here shown equipt with a tongue 19; it will be apparent however that the overlapping bar region need not be confined to the specified contour since it may assume any desired polygonal shape.

The gap 21 along the innermost, inturned flange of the dished bar 16 allows the intersecting end of the bar 17 to be snugly superimposed within the socket 26. After these complementary bar ends are nested together, the entered side tongue 19 is clinched into its contiguous aperture 23 and the depending end-tongue 18 is permanently crimped over the underlying edge of its mated bar in the fashion represented in Fig. 4. It will be observed that the root of the overhanging tenon 19 is sharply bent and the free end thereof brought into substantial alignment with the innermost rail flange 16B, to the end that said free end may be unrestrictedly entered into the aperture 23 without defacing the front face when the overlapping rail web apertures are superimposed as shown in Fig. 1. Each of the overlapping frame corner regions are similarly treated, which provides the perimeter of the interconnected framework with rearwardly upstanding prongs such as 14 and 15 adapted to receive and be inturned over the rear face of the license plate 10 (see Figs. 2 and 4).

It is preferred to have more than one prong embrace each of the marginal edges of the rectangular panel 10; these prongs can be repeatedly bent up to allow of panel replacement. The overall frame dimensions are preferably chosen to make the innermost perimeter of my interconnected bars center in the plate groove 12, the overlapping prongs being kept sufficiently long to reach inwardly over and press upon the rear of such groove-forming wall as shown in Fig. 3. In the pres- 120 125 130

- ent invention, the innermost web flanges are all brought down flush upon the front face of the license plate in an inwardly centered relation to the marginal bead thereof and 5 the separate bar fastening means together with the associated depending prongs, are confined to and located within their respective intersecting bar regions.
- A further important aspect of my frame 10 structure lies in forming up segmental blanks from strip stock that require no further shearing along the longitudinal edges thereof and in so shaping up the respective overlapping channel-like terminals, that no 15 weld or separate keeper means will be required for corner securement purposes. It is not essential however that each segmental bar be equipit with duplicate prongs since certain of such prongs may readily be eliminated without loss of effective plate securement. It will also be obvious that my socket 20 element may be reversely formed by offsetting the bar 17 instead of the bar 16, as shown.
- 25 As applied to the described disclosures, my process of making a built-up segmental framework may include the following steps: (1) cutting up smoothly finished, cold-rolled, flat strip stock into a plurality of complementary bar blanks, preferably provided with 30 prongs; (2) giving the respective blanks a troughlike transverse profile to impart augmented transverse rigidity thereto and simultaneously forming cooperating male and female terminal portions for the respective troughs adapted to nest in crosswise relation; (3) assembling mated pairs of such bars and interlocking the intersecting terminal regions thereof into a fenestrated framework 35 adapted to mount and secure a panel therein; (4) lastly, plating to weatherproof said framework with lacquered cadmium, copper-nickel-chrome or the like bright surface finish without need of initially buffing 40 said strip stock.
- The shape given to my nested bar terminals preferably remains the same irrespective of the blank length and may readily be formed up by the use of extensible, sectional 45 dies adapted to fit different bar lengths. Said method produces a segmental frame structure of which the sections are rigidly secured together and may be applied to uniting intersecting corner regions where the 50 bars are to be obliquely disposed to form a rhomboidal or triangular contour. The defined novel mode of frame manufacture especially lends itself to rapid quantity fabrication at a sufficiently low production cost to 55 enable this article to be profitably retailed through chain store agencies. In the present invention, the intersecting bar terminals are extended to overlie each other in either an external or internal relationship without 60 requiring any separate keeper or interlock- 65
- ing elbow pieces for corner securement purposes. If desired, all my bar blanks may be made alike as regards the terminals thereof by forming one end with tongues as in Fig. 5 while the opposite end thereof is provided with an aperture 23 as in Fig. 6.
- 70 Other advantages inherent in my method are thought apparent to those skilled in this art, also that the corner structure thereof may be variously modified in likewise carrying out my illustrative embodiment, all without departing from the spirit and scope of my invention heretofore described and more particularly pointed out in the appended claims.
- I claim:
1. The method of making adjoined segmental frame-bars and which method includes the following steps, viz: stamping complementary sheet metal blanks from flat, relatively narrow strip stock, an end region of one such blank being provided with an overhanging tongue disposed within the longitudinal edge confines of the strip width without shearing either of the medial strip edge regions and a terminal region of the other blank being apertured to receive said tongue; then forming complementary rectilinear frame-bars by imparting a channel-like transverse profile to the respective blanks and shaping up an offset socket-like terminal portion for one such blank adapted to cooperatively nest therein the terminal region of the other blank in crosswise overlapping relation; and thereupon, adjoining said cooperatively nested terminals into a series of tongue interconnected frame-bars.
  2. The method of making up a framework comprising pairs of adjoined segmental bars and which method includes the following steps, viz: stamping a pair of complementary bar blanks from sheet metal strip stock of which one blank terminates in a prong kept within the width confines of said stock, an end region of one such blank being further provided with an integral tongue and an end region of the other blank being apertured to receive said tongue; then forming complementary rectilinear frame-bars by imparting a channel-like cross-sectional profile to the respective blanks and simultaneously shaping up an offset extension upon an end region of said one blank adapted to overlappingly nest an end region of the other blank; and thereupon, adjoining a series of complementary blanks thus formed into a tongue-interconnected, endless frame structure provided with a plurality of prongs depending from the perimeter thereof.
  3. The process of fabricating a sectional moulding comprising adjoined rectilinear bar-segments and which method consists in the following steps, viz: stamping by intermittently operated die means, a pair of mated sheet metal blanks out of strip stock of uniform width from which the respective blank

ends are severed in appropriate contour to provide for interlocking tongue means for the respective blanks, the overall length of each such blank being determined by the longitudinal feed spacing that is given to the strip stock between the severing period and the blank width in its medial region being kept equal to that of the strip stock; then reforming the respective mated blanks into cross-sectionally dished, rectilinear bar-segments having their respective end regions shaped to nest in crosswise relation; and thereupon, assembling said reshaped blanks into a chain of tongue-interconnected segments.

4. The process of fabricating a sectional frame-work comprising rectilinear segmental bars and which method consists in the following steps, viz: stamping by means of dies, mated pairs of sheet metal blanks out of smoothly rolled strip stock from which said mated blanks are severed and respectively provided with interlocking tongue means; then reforming said blanks into dished bar-segments; and thereupon, plating said bars to impart a bright weatherproof surface finish thereto.

5. The process of fabricating a rounded corner structure for a moulding comprising a pair of rectilinear segments superimposed to intersect in oblique relation to constitute an overlapping bar region of sectorlike shape having an arcuate perimeter together with oppositely disposed radial margins from which the respective segments extend outwardly, and which method consists in the following steps, viz: stamping complementary blanks from relatively narrow strip stock, an end region of each such blank having a rounded contour disposed within the width confines of said stock and one of which segments has clinchable tongue means integrally associated therewith; then placing the rounded segment contours in superimposed alignment and interlockingly clinching the tongue over the other of said segments.

6. The process of fabricating a rounded corner structure for a moulding comprising a pair of rectilinear bar-segments superimposed to intersect in oblique relation to constitute an overlapping bar region of sectorlike shape having an arcuate perimeter and which segments extend oppositely away from the respective radial margins of said shape, and which method consists in the following steps, viz: stamping complementary sheet metal blanks from strip stock, an end region of each such blank having a rounded contour disposed within the width confines of said stock and one of which contours has clinchable tongue means integrally associated therewith; then forming up complementary bar-segments by imparting a channel-like transverse profile to each such blank and upturning the rounded contours thereof into termi-

nal regions adapted to nest cooperatively when said bars are placed in intersecting relation; and thereupon, securing together the intersecting bar region by means of said tongue.

7. The process of fabricating a rounded corner structure for a moulding comprising a pair of rectilinear bar-segments superimposed to intersect in oblique relation to constitute an overlapping bar region of sectorlike shape having an arcuate perimeter and which segments extend oppositely away from the respective radial margins of said shape, and which method consists in the following steps, viz: stamping complementary sheet metal blanks from strip stock, an end region of each such blank having a rounded contour of which one such contour includes a prong extending outwardly therefrom within the width confines of said stock; then forming up complementary bar-segments by cross-sectionally dishing each such blank and upturning the respective rounded contours thereof; and thereupon, placing the upturned contours into nested relation and securing together the overlapping region of the intersecting bars.

8. The process of fabricating a framework comprising intersecting segmental bars of the dished type and which method includes the following steps, viz: stamping a pair of complementary sheet metal blanks from relatively narrow strip stock of which one such blank is provided with an edge indentation adjacent to an end thereof; then forming up complementary bar-segments by imparting a channel-like transverse profile to each of the blanks, the aforesaid indented blank edge providing for a gap in a profile flange of one such bar; and thereupon nesting the other of said bars into said gap in superimposed relation to said one bar and securing together the overlapping region of the intersecting bars.

9. The process of fabricating a corner structure for a moulding comprising a pair of rectilinear bar-segments superimposed to intersect in oblique relation and including an overlapping bar region of polygonal shape of which a marginal edge extends crosswise of one such bar, and which method consists in the following steps, viz: stamping complementary sheet metal blanks from strip stock, an end region of one such blank having a tongue and an inset prong integrally associated therewith; then forming up complementary bar-segments by imparting a channel-like transverse profile to each such blank and offsetting an end region of one such blank to constitute a socketed extension thereon; and thereupon placing the bars in intersecting relationship and securing the bars together by means of said tongue, said offset being disposed to coincide with the crosswise marginal edge of the aforesaid overlapping

shape and the prong being appended to the perimeter of the moulding corner structure.

10. The process of fabricating a corner structure for a fenestrated moulding comprising a pair of rectilinear bar-segments superimposed to intersect in oblique relation and including an overlapping bar region of polygonal shape of which divergent adjacent edges each extend crosswise of the respective bars, and which method consists in the following steps, viz: stamping complementary sheet metal blanks from strip stock, an end region of one such blank terminating in prong means and the other blank having clinchable tongue means kept within the width confines of said stock; then forming up dished complementary bar-segments adapted to intersect in nested relation; thereupon, superimposing said bars in nested relation and clinching said tongue for bar interlocking purposes, the prong being appended to the perimetric region of the aforesaid polygonal shape intermediate the extremities of the diverting adjacent edges thereof; and lastly, mounting a panel behind said moulding and inturning the prongs thereof over a marginal edge of said panel.

In testimony whereof, I have herewith set my hand this 12th day of July, 1932.

30 UDO K. JOHANNSEN.
